(57) CLAIM

The ornamental design for a handle for a stein, as shown and described.

DESCRIPTION

FIG. 1 is a perspective view thereof showing my new design for a handle for a stein,

FIG. 2 is a front view thereof,

FIG. 3 is a bottom view thereof,

FIG. 4 is a top view thereof; and,

FIG. 5 is a left side view thereof, with the right side view being a mirror image thereof.

The broken lines shown are included for the purpose of illustrating the unclaimed portions of the article and form no part of the claimed design.

1 Claim, 5 Drawing Sheets
